A. R. WILSON

CAR WALL CONSTRUCTION

Filed June 22, 1925

UNITED STATES PATENT OFFICE.

ALFRED R. WILSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR-WALL CONSTRUCTION.

Application filed June 22, 1925. Serial No. 38,872.

This invention relates to car wall constructions and particularly to that type in which the wall comprises ribbed or panelled metallic sheets. While such constructions are particularly applicable to car ends they may be also effectually employed as the side walls of the car.

An object of the invention is to produce wall sheets of this character with ribs or panels pressed therein, the conformation of which is designed to impart the greatest rigidity and strength to the sheets. Other objects of the invention, as well as the novel details of construction of the same, will be made more apparent as this description proceeds, especially when considered in connection with the accompanying drawings wherein

Figure 1 is an elevation of a car end constructed in accordance with this invention.

Figure 2 is a sectional view taken substantially on the plane indicated by line 2-2 of Figure 1.

Figure 3 is a sectional view taken substantially on the plane indicated by line 3-3 in Figure 1.

Figure 4 is a similar section showing a modified form of construction.

Figure 5 is a similar section showing still another modified form of construction, and

Figure 6 is a fragmentary elevational view showing a modified form of rib conformation.

While the invention is herein illustrated and described in connection with car ends it will be immediately apparent that it is equally adaptable to all car wall constructions. In the drawings a car end is illustrated and is shown as comprising a plurality of sheet metal plates 10, the adjacent longitudinal edges 11 of which are arranged in overlapping relation and are suitably apertured and secured together as by means of rivets 12. Each sheet is preferably formed with laterally extending flanges 13 to facilitate attachment of the sheets to the side walls of the car, the upper and lower sheets being also suitably attached respectively to the frame members 14 and 15 of the car.

Each sheet is formed with a plurality of panels 16 arranged in spaced planes paral-

lel to the marginal portions 11 of the sheet, these panels being connected to the remainder of the sheet by oblique portions 17 and 55 substantially right-angular portions 18, these panels 16 together with the connecting portions 17 and 18 constituting ribs which are formed by suitably pressing the metal plates 10. In forming the ribs to produce 60 the panel portion 16 inclined portions 19 are formed at the end thereof which connect the panels to the main portion of the sheet, these inclined portions 19 being substantially triangular and flat and angularly disposed with 65 reference to the portions 17 and 18.

In Figure 4 a slightly modified form of construction is illustrated in which the sheets 10' are somewhat wider and consequently a lesser number are employed in forming the 70 car end. In this form the upper sheet is connected to a frame member 14 similar to the upper frame member previously referred to, while the lower sheet 10' is shown as formed integrally with the bottom frame 75 member 15'.

In Figure 5 still another modification is illustrated in which a plurality of sheets 10'' are illustrated, these sheets being of a lesser width than those shown in the first described 80 form, whereby a greater number are employed in forming the car end. The lowermost sheet is shown as connected to a frame member 15'', here shown as a channel bar.

In Figure 6 the rib is shown as formed 85 with a different end construction, the panel 16' being connected to the main part of the sheet by means of an inclined portion 19' rounded with reference to the portions 17' and 18'.

In a car wall construction of the character herein described a greater strength, rigidity and durability is obtained owing to the peculiar conformation of the ribs, a plurality of which are formed in each of the sheets constituting the wall. The panel portions 16, which are parallel to but spaced from the plane of the main sheet and the marginal portions thereof, are joined, on the one hand, by the inclined portions 17 and on the other 95 hand, by the right-angularly arranged portions 18. The composite sheet constituting the wall and comprising a plurality of the sheets 10 rigidly united along their overlap-

ping longitudinal edges constitutes a strongly trussed structure, one which is inherently rigid and capable of withstanding unusually heavy lateral stresses.

5. As shown in the preferred and modified forms of construction herein illustrated, the sheets 10 may be formed of any desired width, the width of the individual sheets, however, determining the number of sheets 10 required in a given wall area. By forming the wall structure of a plurality of separate sheets repair may be made to any damaged portion thereof without necessitating the destruction of the entire wall. Consequently 15 sheets 10 of relatively narrow width are more efficient and preferable. Furthermore, as shown in the forms of the invention herein illustrated, the upper and lower sheets of the wall may be connected to or formed integral with the upper and lower frame members of the car.

While several forms of the invention have been illustrated herein, it will be readily apparent to those skilled in the art that various other forms and modifications of the invention 25 may be resorted to without departing from the spirit and scope of the invention, and to this end reservation is made to make such changes as may come within the pur- 30 view of the accompanying claims.

What I claim as my invention is:

1. In a car wall construction, a sheet metal plate pressed to form a rib extending longitudinally of the plate, each rib having a portion parallel, a portion inclined, and a portion at right angles to the plane of the plate, the said right angularly arranged portion terminating in the plane of the plate.
2. In a car wall construction, a plurality 40 of sheet metal plates having overlapping ad-

jacent edge portions riveted to each other, each plate being pressed to form a rib extending longitudinally of the plate, each rib having a portion parallel, a portion inclined and a portion at right angles to the plane of the plate said two latter portions merging into the plane of the plate. 45

3. In a car wall construction, a sheet metal plate pressed to form a plurality of spaced parallel ribs, corresponding portions of 50 which are similarly arranged, each rib having a portion parallel, a portion oblique, and a portion at right angles to the plane of the plate.

4. In a car wall construction, a sheet metal 55 plate pressed to form a plurality of correspondingly shaped ribs, each rib having portions oblique and at right angles to and merging into the plane of the plate.

5. In a car wall construction, a sheet metal 60 plate pressed to form a plurality of correspondingly shaped ribs, each rib having a portion oblique, and a portion at right angles to the marginal plane of the plate, said portions being arranged in spaced parallel rela- 65

6. A car wall construction comprising a plurality of sheet-metal plates with their longitudinal edges arranged horizontally and in overlapping relation and riveted to each other, each plate being pressed to form a panel parallel to the marginal portion of the plate, a portion at right angles to the plane of the plate connecting one longitudinal edge 70 of said panel to said plate and a portion inclined to the plane of the plate connecting the other longitudinal edge of said panel to said plate. 75

In testimony whereof I affix my signature.
ALFRED R. WILSON.
